Hazel L. Sutcliffe, Kirkwood, Mo., assignor to Husky Corporation, St. Louis, Mo., a corporation of Missouri

Filed May 28, 1965, Ser. No. 85,498

Term of patent 14 years

(Cl. D91—1)

FIG. 1

FIG. 2

FIG. 4

FIG. 1 is a side elevational view of a guard for dispensing nozzle, showing the novel design, the broken-line portions being shown to illustrate its association with a dispensing nozzle, which is included for illustrative purposes only. The opposite side is substantially the same in appearance as the side shown.

FIG. 2 is a top view of the guard.

FIG. 3 is an end view of the guard shown in FIG. 1, looking at same from the left hand end.

FIG. 4 is an end view of the guard shown in FIG. 1, looking at same from the right hand end.

I claim:

The ornamental design for a guard for dispensing nozzle, substantially as shown and described.
